(57) **CLAIM**

I claim the ornamental design for a control unit for a battery module, as shown and described.

DESCRIPTION

FIG. 1 is a front, bottom and left side perspective view of a control unit for a battery module showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and,

FIG. 7 is a right side elevational view thereof.

The broken line in the figure drawings is included for the purpose of illustrating environment and forms no part of the claimed design.
